UNITED STATES PATENT OFFICE

JOHN N. NELSON, OF ROCHESTER, NEW YORK, ASSIGNOR TO UNIVERSAL OPTICAL CORPORATION, OF PROVIDENCE, RHODE ISLAND, A CORPORATION OF RHODE ISLAND

OPHTHALMIC MOUNTING

Application filed April 17, 1930. Serial No. 444,982.

My present invention relates to improvements in ophthalmic mounting, more particularly to the nose guard members thereof and to the method of forming the same.

One object of this invention is to provide a nose guard having a body portion formed of non-metallic material and having a core of bendable metal inserted or imbedded into the body portion and also having a bendable metallic arm with one end portion inserted into this non-metallic body.

A further object of the invention is to form the body portion of the guard of a single piece of non-metallic material such for instance, as celluloid or the like and to insert a blade or other core of metal, preferably by softening the body and then forcing this blade thereinto, and also forcing one end of the bendable metallic arm into this body to securely anchor this end therein.

With these and other objects and advantageous features in view, the invention consists of novel arrangements of parts more fully disclosed in the detailed description following, in conjunction with the accompanying drawing, and more particularly set forth in the appended claims.

In the drawing:

Fig. 1 is an elevation partly broken away, showing the novel nose guards secured to the bridge piece of the mounting;

Fig. 2 shows a block or single piece of non-metallic material with the blade in position to be forced endwise thereinto;

Fig. 3 indicates the blade in dotted lines as having been forced and imbedded into the body portion and showing the entering slot at the end of this body;

Fig. 4 is a perspective view of the bendable metallic attaching arm for the guard, showing the locking notches in one end thereof;

Fig. 5 is a view partly in section showing the metallic blade as inserted into the non-metallic body and the metallic arm having its locking end inserted into one edge of the non-metallic body;

Fig. 6 is an edge view of the non-metallic body indicating the core blade as inserted therein and the bendable arm as extending

from one edge thereof with the edges of the body portion nicely rounded.

It has been found desirable in the construction of ophthalmic mountings to provide the body portion of the nose guard of non-metallic material, thus eliminating any tendency to tarnish or corrode and adding to the comfort to the user, and to the decorative effect, and also to reduce to the minimum the cost of manufacture.

Owing to the fact that it is desirable that the body portion of the nose guard be bendable to conform to the contour of that portion of the face with which it comes in contact, it is necessary that bendable material shall be inserted into the celluloid or non-metallic body portion thereof; and to accomplish this in a simple and effective way, I provide a core which may be made in any suitable form such as a blade, a strip, a wire or metal in other suitable forms, and I insert this metallic core into this non-metallic body, preferably by softening this body either by application of heat or suitable chemicals to such an extent that this core may be forced and imbedded into the body and the opening through which it enters to be subsequently sealed thereby completely concealing the metal in the non-metallic body. I also provide one end of a bendable attaching arm for the body with notches or the like, and also force this prepared end of the arm into the edge of the non-metallic body. Then I subsequently complete the shaping of this non-metallic body preferably by milling or otherwise cutting away the stock, to nicely round the edges and obtain a pleasing contour of this body member; and the following is a detailed description of the present embodiment of my invention and showing the preferred construction by which these advantageous results may be accomplished.

With reference to the drawing, 10 designates the blank of material such as celluloid, zylonite or other similar material, which may be roughed out into a suitable form; I then soften this blank either by the application of heat or the application of suitable chemicals thereto, and I then force a stiffening metallic core into this body 10, which core may be 100

in any suitable form such for instance as a blade 11 sharpened at its end 12, which may be pressed endwise into the larger end of the body; this blade may also be thinned down on all of its edges to facilitate shaping the non-metallic casing surrounding it.

The slot 13 formed by the blade in entering may be sealed and closed to entirely conceal the blade imbedded in the body. I then provide a bendable arm member 14 preferably of metal with one end notched as at 15 and I force this notched end into the edge of the non-metallic body, the softened material being caused to flow into these notches 15 to secure, lock or anchor this end of the arm firmly therein. It is now only necessary to trim and round the edges of the body 10 which is preferably done by a milling operation to remove the surplus stock 20 and form the body with the desired contour with nicely rounded edges.

By this construction, it will be seen that by the use of this metal core in the non-metallic body, I am enabled to bend the body into any desired position and the metal being of a bendable and ductile nature, will cause the body to remain in the bent shape.

Having thus described one illustrative embodiment of my invention and the best mode known to me for carrying out my method, I desire it to be understood that although specific terms are employed, they are used in a generic and descriptive sense and not for the purpose of limitation, the scope of the invention being defined and limited only by the terms of the appended claims.

I claim:

1. A method of forming a non-metallic nose guard body portion with a bendable metallic blade, which consists in softening the body portion and forcing the bendable metallic blade into the body, and inserting the end of a separate attaching arm into the non-metallic body from a direction different from the insertion of said blade while the body is softened to permanently connect the arm thereto.

2. A method of forming a non-metallic nose guard body portion with a metallic core, which consists in softening the body portion, forcing a blade having a piercing entering edge thereinto, sealing the entering opening, and inserting the end of an attaching arm into the non-metallic body while softened to permanently connect the arm thereto.

3. In an ophthalmic mounting, a nose guard having a body portion formed of a single solid non-metallic bendable piece, a bendable metallic blade imbedded within the walls of said body, and a separate attaching arm having one end portion rigidly anchored in said body.

4. In an ophthalmic mounting, a nose guard having a body portion formed of a solid piece of non-metallic material, a bend-

able metallic blade imbedded and sealed within the walls of said body, and a separate bendable metallic arm having one end portion provided with locking means imbedded and anchored in said body.

5. In an ophthalmic mounting, a nose guard having a body portion formed of a solid piece of non-metallic material, a bendable metallic blade having a thin surrounding piercing edge and imbedded and sealed within the walls of said body, and a separate bendable metallic arm having one end portion provided with locking means imbedded and anchored in said body.

6. In an ophthalmic mounting, in combination, a bendable metallic blade of a width greater than its thickness, a separate bendable arm, and a bendable non-metallic covering body surrounding and locking together said metallic blade and one end of said bendable arm, said metal parts being closely adjacent one to the other.

7. In an ophthalmic mounting, a nose guard having a body portion formed of a single solid non-metallic bendable piece, a bendable metallic blade imbedded within the walls of said body, and a separate metal attaching arm having one end portion rigidly anchored in said body.

In testimony whereof I affix my signature.

JOHN N. NELSON.
